UNITED STATES PATENT OFFICE.

GEORGE W. LEE, OF SCHENECTADY, NEW YORK.

DESIGN FOR A SASH-CORD FASTENER.

SPECIFICATION forming part of Design No. 19,719, dated March 25, 1890.

Application filed February 26, 1890. Serial No. 341,887. Term of patent 7 years.

To all whom it may concern:

Be it known that I, GEORGE W. LEE, a citizen of the United States, residing at Schenectady, in the county of Schenectady and State 5 of New York, have invented and produced a new and original Design for Sash-Cord Fasteners; and I do hereby declare the following to be a full, clear, and exact description of the invention, such as will enable others skilled 10 in the art to which it appertains to make and use the same.

The design relates to a sash-cord fastener; and it consists of a sash-cord fastener distinguished by its peculiar shape, which will be 15 hereinafter set forth and claimed.

The accompanying drawing is a front perspective view of the sash-cord fastener.

In my newly-designed sash-cord fastener

the body A has a general oval or elliptical configuration, which is broken at one point to 20 leave the open space a. The front edge of the oval body surrounds a face wherein are the circular opening B and the elongated parallel-sided opening C, running from the opening B to the space a. On the surface of the oval 25 body there are a number of cross ribs or ridges b.

What I claim is—

The design for a sash-cord fastener, as 30 herein shown and described.

In testimony whereof I affix my signature in presence of two witnesses.

GEORGE W. LEE.

Witnesses:

JOHN V. WEMPLE,
H. W. DENNINGTON.
